UNITED STATES PATENT OFFICE.

LEWIS H. EICHELBERGER, OF PLAINFIELD, NEW JERSEY, AND RAYMOND A. WALTER,
OF FROSTBURG, MARYLAND, ASSIGNEES TO RANSOME CONCRETE MACHINERY COM-
PANY, OF NEW YORK, N. Y., A CORPORATION OF NEW YORK.

APPARATUS FOR AND METHOD OF MINING.

1,334,894.

Specification of Letters Patent. Patented Mar. 23, 1920.

Application filed October 27, 1916. Serial No. 128,049.

To all whom it may concern:

Be it known that we, LEWIS H. EICHELBERGER and RAYMOND A. WALTER, citizens of the United States, and residents of the 5 city of Plainfield, in the county of Union, State of New Jersey, and the town of Frostburg, in the county of Allegany, State of Maryland, respectively, have invented certain new and useful Improvements in Apparatus for and Methods of Mining, of 10 which the following is a specification.

The improvements relate to the mining of coal and all other minerals and have for their objects, among others, the provision 15 of means whereby mining operations of this character may be carried on economically and advantageously, and with a greater degree of safety to the miners employed in such work, particularly where 20 the veins, seams or strata are relatively narrow, thin or low and the surrounding conditions such as to render the work difficult, expensive or dangerous. They involve the employment of concrete mixing 25 and placing apparatus such as that shown in Letters Patent of the United States, No. 1,097,084, granted May 19, 1914, and in co-pending applications filed August 30th and September 5th, 1916, and numbered 117,603 30 and 120,221 respectively, although the improvements are not limited to the use of such apparatus.

Heretofore it has been common practice in the mining of coal to drive parallel galleries or headings through the bed or seam on the same horizontal plane and parallel therewith and extending a suitable distance above or below the same, or both above and below it, so as to give ventilation and clearance for operatives, and cars and other appliances, and then to run lateral headings therefrom in both directions through the bed. These lateral headings are connected at relatively short intervals by room headings, and the coal blocked out in this manner is then removed through these headings or galleries. As the lateral cross headings and room headings are of approximately the same height as the main headings and 50 the strata through which they are cut above and below the coal seam is usually rock, the expense of driving them is a very large item in mining operations, and the thinner the vein of coal the greater the relative

cost of the headings and the greater the 55 cost of mining the coal. The more frequent these headings also the greater the cost of mining, and it is therefore sought to have them as far apart as possible without unduly increasing the cost of removing 60 the coal blocked out by them, or other disadvantages. To such an extent do this and other items enter into the mining cost that the expense of working seams having a height of less than three feet is generally 65 prohibitive, even where mining machines of the "Longwall" type are employed.

Again one of the greatest difficulties in mining coal is found in the provision of proper means for sustaining the overburden 70 or controlling its subsidence after the coal has been removed. This is usually provided for by leaving coal pillars at sufficient intervals and by the use of wooden posts. But the use of coal pillars and 75 posts is wasteful of coal and dangerously weak, and the work of removing the pillars after the coal from the rooms has been removed quite often results in loss of life. In recent years over a thousand lives have 80 been lost annually in the United States on account of roof falls. In addition to this the placing of the timber and the size and location of the coal pillars interfere with the working of the seam to such an extent 85 that a large part of the time of the men is consumed in handling mine cars between the heading tracks and the working faces of the rooms; in placing timbers; in blasting and removing overlying or underlying rock 90 to provide clearance for the cars; in loading and unloading, moving and sumping or holing in the mining machines; in providing for the removal of water seeping into the mine; in providing for the circulation 95 of air; and in constructing and operating the network of tracks and switches required for the transportation of the coal after it is mined.

This will be understood when it is considered that, under the common practice, as much as one-third of the coal must be left for pillars to support the roof and prevent it from breaking and falling; that the machine by which the coal is undercut, working 100 along the working-face of the room, must be stopped, loaded on its truck, transported to the heading, around the portions of the bed

or seam left for pillars up into the next room, unloaded, sumped in and adjusted for the run across the next face, which operation must be repeated for every room cut; these rooms approximating 25 feet in width; that, where the seam of coal is of insufficient height to permit the entrance of cars, the necessary clearance must be obtained by blasting and removing overlying or underlying rock, not only in the headings, lateral cross headings and room-headings, but also in every room; that at the entrance to each room the train of empty mine cars must be stopped, a car detached and taken into the room, the loaded car removed and attached to the returning loaded train; that expensive mine posts must be hauled to all parts of the mine and there erected at frequent intervals, this part of the work requiring the services of skilled men; that this timber has but a short life and must be continually renewed; that an independent system of drainage with its expensive pipe lines, pumps and connections must be provided for every room; that several walls of wood, concrete, brick or other material must be constructed across the openings between rooms to maintain and properly direct the air currents, and that a separate switch and track must be constructed in each room.

It is the purpose of the present improvements to overcome these and other disadvantages by providing means for forming concrete supporting walls as the work of removing the coal progresses, which are so formed and placed and of such proportions that they not only support the roofs and prevent falling, creeping and squeezing, but dispense with many headings, facilitate the operation of machines and conveyors, which when arranged and used in accordance with the present improvements will reduce the use of explosives to a minimum and increase the efficiency of the operations at least one hundred per cent., by simplifying the construction and operation of tracks and cars; and by centralizing the work thereby making possible better supervision and inspection and obtaining other advantages.

Under the improved system, after opening the mine, a pair of main headings are driven on the pitch of the seam, to the limits of the property, if desired. Parallel block headings are driven off these headings, on the strike at intervals of about five hundred feet. Two conveyors of special design two hundred and fifty feet in length are then placed in the main heading air course with their discharge ends over the center of each block heading.

A "Longwall" chain machine is now introduced and makes an undercut of from four to six feet extending along the main air course two hundred and fifty feet on both sides of the block headings. The coal is then

drilled and the holes charged and fired, and the coal is then removed by the conveyors which carry it to the mine cars on the block heading. After the entire breast of from four to six feet has been loaded the mining machine and conveyer are moved ahead the width of the cut and a concrete supporting wall, composed of separate sections, extending from roof to bottom, is built across the face immediately back of the conveyer on vertical lines; thus eliminating entirely the use of perishable and expensive timber and the resultant dangers due to the insufficient support afforded the roof, to the failures of timber and necessities for replacements. This operation is repeated until the coal has been entirely removed, the system enabling the operators to remove substantially one hundred per cent.

It will be seen that by so proceeding as to make two cuts of two hundred and fifty feet in length without interruption, the mining machine need be handled, moved and started but once, instead of twenty times as where pillars must be left making the rooms and the corresponding cut across the face but 25 feet wide, and the work of loading and unloading the machine this number of times avoided. The endless conveyors also will carry the coal the entire distance, since there is no obstruction, and it is therefore possible to have the operation of loading the coal on the cars for the entire block conducted directly on the block headings. It is further unnecessary to cut headings across what are here termed the block headings, for the work can be carried on between two parallel headings running off the main heading for a great distance, without disadvantage, by simply advancing the conveyors to follow up the work of cutting and loading so that they will receive the coal and carry it to the block headings at a point immediately behind the breast on either side. In practice empty cars are run into the block headings and placed underneath the ends of the conveyors, after which they are loaded and moved out into the main headings and drawn out of the mine. It will be noted that by this method only half the number of headings and no rooms at all will be required, resulting in the elimination of at least half the rock work as compared with the common practice. It will be necessary to maintain only a small percentage of the number of tracks and switches for the same tonnage. The drainage and ventilation and hauling will be proportionately simplified.

The method of constructing the concrete pillars or props is as follows:

A series of hollow forms made in a plurality of vertical telescoping sections are provided. These forms are placed in a row parallel with the main heading and connected with a mixing and conveying appa-

ratus which may be located at the surface above the main heading, so that the conduit and branch conduits will run vertically down to the said heading and supply the concrete to the forms by air pressure and gravity. Each form has a tap hole by which the concrete conduit is connected therewith so that it can be quickly filled, and also has a removable side next to the main heading. 10 The forms after being filled are allowed to stand until the concrete therein has set to form pillars. The removable side is now taken off and the form pushed forward to a position behind the next cut, each form being adjusted to compensate for any slight variation in the thickness of the seam by telescoping or extending its parts. The removable side is now placed in position again and the form again filled with concrete to 15 make a pillar or post. This operation is repeated, the line of concrete posts advancing as each section of the bed of coal is cut and extracted until the property is exhausted. 20

25 The endless conveyers employed may be of ordinary type, but it is preferred to use a conveyer having the flights to be loaded at the bottom and returning at the top, so that it will be necessary for the miner in loading the conveyer to lift the coal a few inches only. This conveyer has a continuous back of sheet metal which prevents the coal from falling out, but permits it to be discharged into the cars at the end. The cutters and conveyers are supplied with power by an air compressor and compressed air conduit or from an electric generator and suitable conductors operating motors in connection therewith, or in any other suitable 30 manner.

In order to make the description of the method or process more clear it is illustrated in the accompanying drawings, forming a part hereof, in which Figure 1 is a plan showing mine workings conducted in accordance with the improvements; Fig. 2 is a vertical section of a part of the same on a greatly enlarged scale, and Fig. 3 is a plan of the subject-matter of Fig. 2 with adjacent parts. 45

The main heading is indicated by the letter M, the cross-headings by the letter C, the blocks in which the coal is being cut and removed by B, B' and B², the tracks in the main heading by the letter T and the tracks in the cross-headings by the letter T'. 50

In the blocks B it is assumed that there is a light overbear and that the character of the roof is favorable, so that round posts P may be used. In the lower half of the block marked B' the overbear is assumed to be medium heavy, and therefore heavy rectangular posts P' are employed. In the upper half of the blocks marked B' the posts 60 are in the form of short walls P² such as

are calculated to sustain a very heavy overbear.

The concrete conduit for filling the forms employed is indicated at A, and it will be understood that this conduit extends to the 70 surface of the ground above the workings and has branch conduits for filling the various forms. The forms are indicated at D (Figs. 2 and 3), and the connection for the concrete conduit at F. These forms are 75 placed in rows, filled, and the concrete allowed to set, and other forms in staggered relation placed intermediate and in advance of them so that the rows and forms may be advanced as the work progresses alternately. 80

The roof or overbear is marked G, the floor H, and the coal seam J, while the cutter making the undercut E, is marked L, and the conveyer K. Cars in the cross-headings are indicated at N, and these cars 85 after being filled are run over the tracks T' to the main track T. The arrow in the main heading M indicates the line of progress, and the removal of coal and drainage is in the opposite direction. 90

The use of this method results in a great saving of human life, the recovery of all the coal or ore in the mine, the economical development of thin seams and veins, the saving of labor, equipment and power and better opportunities for ventilation and drainage. In addition to this it prevents the cracking and breaking up of the surface over the mine, and the resulting damage to 95 improvements and other property thereon, 100 as well as the drainage of water courses.

The size, form and placing of the concrete pillars will depend on the character of the roof and other conditions, and the other steps in the method herein described may 105 be otherwise varied as these conditions require without departing from the scope of the invention defined in the claims.

The method of mixing and supplying the concrete for the formation of pillars and posts in itself has a number of advantages in addition to those hereinbefore referred to. 110

With it the mechanisms and the materials employed in making the concrete may be located at a point where they can be conveniently placed and utilized without interfering in any way with the mining operations, and the concrete may be used within the mine for grouting water veins, filling 115 rock fissures and for other purposes. 120

What we claim is:

1. The herein described method of mining which consists in driving a main heading into the seam, driving lateral headings from said main heading into the seam, placing conveyers in said lateral headings and operating them along the said headings to the main heading, removing a breast or strip of the mineral parallel with the main heading and conveying the mineral thus removed 125 130

continuously to the conveying means in the lateral headings, forming posts of cementitious material and of height varying according to the height of the room from which said mineral has been removed in the space left by said removal, removing another strip or breast in similar manner, then placing other similar posts in similar manner in the space thus made and repeating these operations until the desired amount of mineral has been removed.

2. The herein described method of mining which consists in driving a main heading into the seam, driving lateral headings from said main heading into the seam, placing conveyers in said lateral headings and operating to the main headings, removing a breast or strip of the mineral parallel with the main heading and conveying the mineral thus removed continuously to the lateral headings, forming in place posts of cementitious material and of height varying according to the irregularities in the height of the room from which said mineral has been removed, removing and conveying another strip or breast in similar manner, then placing other similar posts in similar manner in the space thus made, and repeating these operations until the desired amount of mineral has been removed.

3. The herein described method of mining which consists in driving a main heading into the seam, driving lateral headings from said main heading into the seam, placing conveyers in said lateral headings to the main heading, removing a continuous strip of the mineral parallel with the main heading and extending from one lateral heading to another, and conveying the mineral thus removed continuously to the lateral headings, forming *in situ* posts of cementitious material and of varying length according to the variations in the height of the room from which said mineral has been removed, removing and conveying another strip in similar manner, then forming and placing other similar posts in similar manner in the space thus formed, and repeating these operations until the desired amount of mineral has been removed.

4. The herein described method of mining which consists in driving a main heading into the seam, driving lateral headings from said main heading into the seam, placing conveyers in the said lateral headings to the main heading, removing a breast or strip of the mineral parallel with the main heading and between the lateral headings and conveying the mineral thus removed continuously to the lateral headings, forming posts of fluent cementitious materials in the room from which said mineral has been removed, removing another strip in similar manner, then making other similar posts in similar manner in the space thus formed,

and repeating these operations until the desired amount of mineral has been removed.

5. The herein described method of mining which consists in driving a main heading into the seam, driving lateral headings from said main heading into the seam, placing conveyers in the said lateral headings to the main heading, removing a breast or strip of the mineral parallel with the main heading and between the lateral headings, and conveying the mineral thus removed continuously to the lateral headings, forming posts of fluent cementitious materials in the room from which said mineral has been removed by conveying through a conduit leading from a point removed from the headings and filling in from floor to roof thereof at intervals with said materials and confining them while permitting them to set, removing another strip in similar manner, then making other similar posts in similar manner in the space thus formed, and repeating these operations until the desired amount of mineral has been removed.

6. The herein described method of mining, which consists in driving a main heading and parallel lateral headings extending therefrom at intervals into the seam, removing a strip along the breast of the seam between the headings, conveying concrete aggregates in a continuous stream from a point exterior to the workings to the room made by said removal, and forming posts therein by filling in from floor to roof at intervals with said concrete and confining it laterally until it sets, then removing another strip and repeating the post forming process.

7. A system of mining equipment comprising hollow extensible and openable concrete forms, adapted to be placed in a chamber formed by the removal of a section of the seam, and to extend from floor to roof thereof and to be adjusted to so extend at points in the chamber of different height due to inequalities of the floor or roof, a conduit for concrete leading to the said chamber from a point outside the workings, and said forms provided with openings through which concrete may be supplied through the said conduit to the interior thereof to fill the same, the construction and arrangement of the forms being such that they may be removed and advanced to follow up the enlargement of the chamber due to removal of the mineral of the seam, placed in position as before and again filled, whereby a series of concrete posts or pillars may be formed behind the work of removing the mineral step by step as the said work progresses.

8. The herein described method of mining, which consists in driving a main heading and parallel lateral headings extending therefrom at intervals, removing a strip along the breast of the seam between the headings by undercutting and breaking

down the mineral and conveying it by suitable means continuously from points adjacent its original site to the headings, conveying concrete aggregates in a continuous stream from a point exterior to the workings to the room made by said removal, and forming posts therein by filling in from floor to roof at intervals with said concrete and confining it laterally until its sets, then

removing another strip, advancing the cutting and conveying means toward the breast of the seam still intact, and repeating the post forming process.

Witness our hands this 4th day of October, 1916, at the city of New York, in the 15 county and State of New York.

LEWIS H. EICHELBERGER.
RAYMOND A. WALTER.
